COLOR SLIDE VIEWER

Arthur R. Bentsen, Providence, R. I., assignor to General Electric Company, a corporation of New York

Application April 29, 1955, Serial No. 35,750

Term of patent 14 years

(Cl. D61—1)

Fig. 1.

Fig. 4.

Fig. 3.

Figure 1 is a front elevational view of a color slide viewer embodying the new design;

Figure 2 is a right side elevational view of the viewer of Figure 1;

Figure 3 is a top plan view of the viewer of Figure 2; and

Figure 4 is a perspective view of the viewer of Figure 1.

I claim:

The ornamental design of a color slide viewer, substantially as shown.
